UNITED STATES PATENT OFFICE.

JAMES M. TIERNAN, OF ASHEVILLE, NORTH CAROLINA.

AUTOMATIC FIRE-EXTINGUISHER FOR RAILROAD-CARS.

SPECIFICATION forming part of Letters Patent No. 371,642, dated October 18, 1887.

Application filed March 21, 1887. Serial No. 231,796. (No model.)

To all whom it may concern:

Be it known that I, JAMES M. TIERNAN, a citizen of the United States, residing at Asheville, in the county of Buncombe and State 5 of North Carolina, have invented a new and useful Automatic Fire-Extinguisher for Car Stoves and Lamps, of which the following is a specification.

My invention relates to an automatic fire-extinguishing apparatus suitable for use in connection with a car-heater, and has for its object to provide means for instantaneously projecting a gas which will not support combustion upon a fire or flame upon the occurrence of 15 an accident to the car or vehicle sufficient to disturb its equilibrium; and it consists in the matters hereinafter described and particularly pointed out.

Figure 1 represents a side elevation, partly 20 in section, of the extinguishing apparatus. Fig. 2 is an enlarged view of a portion of the grooved floor. Fig. 3 represents a side elevation of the valve, valve-cover, gas-pipe, cock, and operating-lever on an enlarged scale.

A indicates a tank or receptacle for the extinguishing-gas, which may be introduced into said tank in any well-known way. It has been heretofore proposed to hold such gas under compression, ready for instant use in extinguishing a fire on the movement of a valve, and it has also been proposed to provide means for the automatic generation of a gas—such as carbonic-acid gas—on the occurrence of an accident to the vehicle conveying the extinguishing apparatus sufficient to open a communication between different compartments containing gas-generating materials. It is obvious that a tank containing compressed gas will afford means for prompter action than a gas-generating tank. The present invention, however, does not simply relate to the means of supplying gas, but to devices for automatically opening communication between a source of gas-supply and the chamber or space in which a 45 fire or flame is located.

A car-stove is denoted at E, which may be of any approved pattern, the drawings barely indicating a chamber or space, which may be over a fire or flame which it is desired to extinguish upon the occasion of the overturning of the tank or of the vehicle or chamber in which the tank is located, or upon the occur-

rence of a collision or other accident of such character as to upset or break a stove or lamp. Below the tank is a comparatively shallow 55 chamber having a floor, D, provided with grooves or channels h, which cross each other, as indicated in Fig. 2. The number of the grooves is not material, though there should be at least two, and if but two they are preferably made to cross each other at right angles. At their intersection an opening, b, is provided, through which a chain, f, passes. This chain is connected with the lever F at any suitable point, as g, and has its opposite end fastened 60 to a bail, e, of a cup or cover, G. This bail is preferably secured to pivots e' in such manner as to move freely on said pivots, though a rigid connection of any kind may be used. Under the cover a ball is placed so as 65 to rest at the intersection of the grooves and over an opening, b. The chamber containing the extinguishing material is connected with a fire or flame chamber by a pipe, H, which may be composed of a flexible part, a, made 70 of gutta percha or other suitable material, and a rigid part, a', made, preferably, of a non-corrodible metal or alloy. The pipe H is provided with a cock, to an extension of which the lever F is attached in such manner that the 75 upward movement of the end g of said lever opens the cock and establishes communication between tank A and chamber E.

The tank, pipe, and cock may be made of any suitable material, which should, however, 80 be of a character to resist the corrosive effect of any gases that are used or any substances that may be carried by suspension in such gas or gases.

The operation of the extinguisher can readily be understood from the foregoing. The tank having been supplied with an incombustible gas—such as carbonic acid, preferably under a considerable degree of pressure—or with means for rapidly generating gas—such as are well known and have been heretofore used in extinguishing apparatus—and the lever F and chain f having been adjusted to a position substantially such as indicated in the drawings, the cock in pipe H is kept closed by 90 the weight of the lever and the apparatus is in readiness for operation whenever from any cause the ball may be caused to move from its seat with sufficient force to move its cover and

the chain connecting the cover and the lever. The ball is smaller than its cover, and is supported to move freely within its cover. If it is not moved with sufficient momentum to carry before it the cover and chain, it drops back upon its seat. An overturning of a car in which the apparatus is placed, or the shock of a severe collision, will impel the ball in one direction or another and along one of the grooves *h* with sufficient force to push before it the cover and draw up the chain and open the cock in pipe *H*, whereupon the extinguishing-fluid will immediately flow through said pipe into the fire-chamber at *E*. Under some conditions the cover might perhaps be used independently, and might perhaps operate to draw up the chain and lever without the aid of the ball; but the latter is essential to the most successful operation. Its initial movement is not hampered by any weight, and, being free to move through a small space, it acquires sufficient momentum to act efficiently in raising the lever and opening the cock.

Pressure in the tank *A* is not essential to the operation, since a heavy extinguishing-fluid will be carried down by gravity if the tank be placed above a fire-chamber. The tank can be placed in any convenient position and secured to its support by the usual means. The flexible portion of pipe *H* provides for the easy adjustment of the position of the tank and connected parts with relation to the stove or lamp. An independent cock may be provided in pipe *H* above the cock before described for the more secure and convenient closing of said pipe when desired.

Having thus described my invention, what I desire to claim and secure by Letters Patent is—

1. The combination, in an extinguishing apparatus, of a car-stove, a gas-tank, a discharge-pipe provided with a cock and connected lever, a ball supported at the intersection of grooves in a supporting-floor, said supporting-floor, a cover for the ball, and a chain connecting the cover and the lever, substantially as specified. 40

2. The combination, in an extinguishing apparatus, of a gas-tank, a discharge-pipe provided with a cock and connected lever, a ball resting at the intersection of grooves in a supporting-floor, said supporting-floor, a cover for the ball, and a chain attached to the cover and extended through a perforation in the floor to the free end of the lever, substantially as set forth. 50

3. In an extinguishing apparatus, the combination of the ball, the supporting-floor, the cover, the chain, the lever, the pipe and cock, and the gas-tank, substantially as specified. 55

4. In an extinguishing apparatus, the combination of the grooved floor, the ball, and the cover, substantially as set forth, whereby the ball and cover are moved in the direction of one of the grooves upon the tilting of the floor. 60

5. In an extinguishing apparatus, the combination of the grooved supporting-floor, the ball resting at the intersection of the grooves, the cover provided with a pivoted bail, the chain connected to the bail and extended through an opening at the intersection of the grooves and attached to the lever, the lever, the gas pipe and cock, and a car-stove, substantially as set forth. 65 70

J. M. TIERNAN.
